*H. Collins,
Shutter Worker.*

No 15,064.

Patented June 10, 1856.

UNITED STATES PATENT OFFICE.

HIRAM COLLINS, OF SALISBURY, MASSACHUSETTS.

SHUTTER-OPERATOR.

Specification of Letters Patent No. 15,064, dated June 10, 1856.

To all whom it may concern:

Be it known that I, HIRAM COLLINS, of 5
Salisbury, in the county of Essex and State
of Massachusetts, have invented a new and
Improved Mode of Opening and Closing
Window Blinds and Shutters Without
Raising the Sashes; and I do hereby 10
declare that the following is a full, clear, and
exact description of the same, reference be-
ing had to the annexed drawings, making
a part of this specification, in which—

Figure 1, is an end view of a window
casing partially bisected, with a shutter at-
tached in an open or partially open state
15 the lower hinge or bearing being bisected.
Fig. 2, is a front view of ditto. Fig. 3, is a
horizontal section of ditto, (x) (x) Fig. 1,
showing the plane of section.

Similar letters of reference indicate cor-
20 responding parts in the several figures.

My invention consists in having an in-
clined rod placed in one of the stiles or side
pieces of the casing, said rod having its
lower end bent upward and fitted within
25 a socket, which forms the lower bearing or
hinge of the shutter or blind. By turning
the rod, the shutter or blind may be opened
or closed without raising the sash, as will be
hereinafter shown and described.

30 To enable those skilled in the art to fully
understand and construct my invention, I
will proceed to describe it.

A, represents a casing of a window or
blind, and B, is a shutter or blind attached
35 to the casing.

The upper end of the shutter or blind is
attached to the casing by an ordinary hinge
(a), but the lower part of the shutter or
blind has a socket (b) fitted to it, said
40 socket being formed of a plate bent similar
to a loop, so as to form a chamber or recess
(c) in the shutter when the plate is attached
to it, see Figs. 1, and 3. The socket may be
formed of cast metal, this would probably
45 be preferable, as the upper part of the
socket should be closed, or have a top or

cover, as shown at (d), Fig. 1. The back
part of the socket (b) projects a short dis-
tance beyond the back edge of the shutter or
blind, and an aperture is made at its lower 50
end to receive the bent or upright portion
(e) of a rod C, which passes obliquely
through one of the stiles of the casing A, as
shown clearly in Fig. 1. The inner end of
the rod C, has a knob D, upon it, the lower 55
end of the knob resting or bearing upon a
plate (f) fitted in the stile. Longitudi-
nally through the knob D, there passes a pin
(g) which may be shoved in holes (h) in
the plate (f) in order to secure the shutter 60
or blind in an open or closed state. Holes
may also be made in the plate (f) so that
the shutter or blind may be secured at inter-
mediate points between an open and closed
state.

65 From the above description it will be seen
that by turning the rod C, at the inner side
of the stile, the lower bent portion (e) of the
rod will actuate the shutter or blind, and
cause it to open or close according to the 70
direction in which the rod is turned.

The above device is simple, efficient, and
economically made and applied, there are
no parts liable to get out of repair, and but
little power is required to actuate the shut-
ter or blind.

Having thus described my invention,
what I claim as new and desire to secure by
Letters Patent, is,

Opening and closing the blind or shutter 80
B, by means of the inclined or oblique rod
C, which passes through the stiles of the
casing, and having its lower or outer end
bent and fitted within a socket (b) attached
to the lower part of the shutter or blind, the 85
rod and blind being secured at desired
points by means of the pin (g) in the knob
D, substantially as shown and described.

HIRAM COLLINS.
